UNITED STATES PATENT OFFICE.

SIEGFRIED HELD, OF CHICAGO, ILLINOIS, ASSIGNOR OF ONE-HALF TO ADOLPH KAESTNER, OF CHICAGO, ILLINOIS.

APPARATUS FOR OZONIZING FLUIDS.

1,420,838.

Specification of Letters Patent. Patented June 27, 1922.

Application filed May 25, 1918. Serial No. 236,520.

To all whom it may concern:

Be it known that I, SIEGFRIED HELD, a citizen of the United States, residing at Chicago, in the county of Cook and State of Illinois, have invented certain new and useful Improvements in Apparatus for Ozonizing Fluids, of which the following is a specification.

My invention relates to improvements in apparatus for ozonizing fluids and has especial reference to convenient devices of this character for purifying water.

One of the objects of my invention is to provide an ozonizing structure designed for purifying water and especially adaptable for domestic or home use.

In my water purifying apparatus I employ a filter to remove all of the solid matter held in mechanical suspension in the water, and then pass the water into a compartment wherein it encounters ozonized air. The incoming air and water are then passed through a suitable mixing chamber wherein the ozonized air becomes thoroughly 25 mixed and incorporated with the water.

Contact of the ozone with the pathogenic bacteria and *Bacilli coli* of the contaminated water completely destroys it and removes all putrescible and other offensive organic matter and odoriferous gases, thus rendering the water hygienic, wholesome and fit for human consumption.

To enhance the desirable health giving qualities and to improve the color of the water it is advantageous to treat it at the rate at which it is being consumed and to avoid the necessity of providing a power-driven means for introducing the ozonized air into the body of flowing water I utilize an inspiriting effect of the moving column 40 of water to draw the air through the ozone generator and into the mixing chamber.

In carrying these features of my invention into effect I close an electric circuit to energize the ozone generator by an instrumentality, usually a manually operable means, such, for example, as a lever or handle of a bibb or faucet, which is movable to open a valve controlling the water supply.

50 In the particular embodiment illustrated in the accompanying drawings which form a part hereof, the device is shown to be self-contained and all that will be requisite to its use is that when being installed it be connect-

ed to an electric circuit of suitable character 55 and to the water supply.

In the accompanying drawings, Fig. 1 shows a front elevation of the device.

Fig. 2 is a longitudinal central section taken on line 2—2 of Fig. 1. 60

Fig. 3 is a vertical section taken on line 3—3 of Fig. 4.

Fig. 4 is a central vertical section taken on line 4—4 of Fig. 3.

Fig. 5 is an enlarged section showing the 65 separable electrical connections and taken on line 5—5 of Fig. 4.

Fig. 6 is an elevation of the lower part of the device shown in Fig. 3.

Fig. 7 is an enlarged section taken on line 70 7—7 of Fig. 6.

Fig. 8 is an enlarged sectional view of the electric switch, for controlling the circuit for the valve opening mechanism.

Fig. 9 is an enlarged transverse section of 75 the mixer, taken on line 9—9 of Fig. 7.

Fig. 10 is an enlarged central and vertical section of the ozone generator, taken on line 10—10 of Fig. 4.

Fig. 11 is a section of the shut-off valve 80 and the connection for the water conduit taken on line 11—11 of Fig. 6.

Fig. 12 is an elevation of the device shown in Fig. 11.

In all the views the same reference characters are employed to indicate similar parts.

20 is an air tight water receptacle having an arcuate head 21 and an open bottom. A spider plate 22 having a series of paneled openings is inserted in the bottom end of the 90 casing and is provided with a circumferentially extending bead 23. A filter plate 25, having its peripheral edges surrounded with a rubber band 26, closes the bottom of the water receptacle. A cup-shaped member 27, 95

of the receptacle, is secured to the main portion thereof by a series of hooks 28 and by threaded rods 29, having eyes 30 engaging the hooks and taking through perforations 31, the edge of said cup-shaped member being held in place by means of winged nuts 32. This cup-shaped member is also provided with an inwardly-projecting circumferential bead 33 bearing against the side of the rubber band 26 and thus water tight connection is made between the cup-shaped member 27 and the interior of the water receptacle 20.

105 Cup-shaped member 27 con-

tains two scrapers 34, there being one on either side of the axial center, yieldingly pressed against the filter plate 25 by a spring 35 which surround a central stud 36, and 5 which passes through the lower wall 27 of the cup-shaped member. A handle 37 is the means by which the scrapers or knives may be rotated to clean the lower surface of the filter plate. In the side wall 38 of the cup-shaped member is a water conducting fitting 39, controlled by a stop cock 40.

The water receptacle 20 is provided with an inset wall 41 closed to the main portion of the receptacle, as at 42 and 43, thereby 15 providing a chamber 44 within which to contain the working mechanism of the apparatus.

A cover plate 45 overlies the opening in the chamber 44 and is connected to the main 20 portion 20 of the water receptacle, as at 42 and 43. It is preferably locked in position, by means of the lock 46, so that it may not be removed, the interior mechanism thereby becoming non-accessible to unauthorized 25 persons.

A water discharge spout 48 is secured to the front wall, or to the cover 45 of the compartment 44, and communicates by a fitting 49, with the casing 50, which contains the water and ozone mixing chamber 51. The 30 stop cock fitting 52 is connected to the bottom wall 41, surrounding the chamber 44, and is provided with a shut-off valve 53, the stem 54 of which is accessible through an opening 56 provided for the purpose in the cover 45. The upper portion of the fitting 52 is annularly enlarged, as at 57, for a connection of a fitting 58, therewith, by a screw 59. A water conduit 60 passes through the 35 parts 57 and 58 into a pipe 61. The screw 59 is also accessible through an opening 63 provided in the cover 45 for that purpose. A gasket 64 is placed between the fitting parts 57 and 58 to make a water tight joint. The pipe 61 is secured to a fitting 67 that enters a chamber 68 in which the water and ozone are mixed, and which is surrounded by a fitting 69 that is connected to another fitting 70, by a union 71. A valve 72 is 40 located inside of the chamber 68 and controls a port 73 through which the water is admitted into a nozzle 75. The valve stem 76 passes through the upper end of the casing 69 and through a suitable packing 77. The upper end of the shaft or spindle 76 is 45 provided with a head 78 having collars 79 and 80 and a space 81 in which is contained the forked ends 82 of a lever 83, that is pivoted, as at 84, to a bracket 85, fixed to a ring 86, that is secured to the upper end of the casing 69, as by screw 87. The valve 72 is 50 normally held closed on its seat 73 by a spring 88.

The valve is opened by an electro-solenoid 55 89, having an axially reciprocatable core 90,

from which projects a stem 91. The stem 91 is provided on its upper end with a head 92, slotted for the end of the lever 93 and containing, preferably, a roller 94. The lever 93 is also pivoted, as at 95, and is provided 70 with a slotted downturned end 96 and is also, preferably, provided with a roller 97 for engaging the upper surface of the lever 83. Now it will be manifest that when the core 90 is raised by the energized electro-magnetic solenoid 89, the outer end of the lever 93 will be raised and the lower end 96 will be depressed, thereby depressing the outer end of the lever 83 and raising the inner end 82, opening the water control valve 80 75 72 and when the solenoid core 90 returns to its normal position the spring 88 will automatically close the valve 72, thus shutting off the water supply. The casing 98, surrounding the chamber 70, is connected to the 80 casing 50 containing the mixer 51, as at 99.

The ozone generator 100, shown in cross section in Fig. 10, and which constitute the subject matter of my copending application, Serial No. 228,326, filed April 13, 1918, is 90 supported on a plate of insulating material 101 by standards 102, 103 and straps 104, 105. The insulating plate 101 is secured to the cover by means of standards 106, 107, 108 and 109.

The air intake end of the ozonizing device 100 is surrounded by an annular casing 110 and the discharging end 111 for the ozonized air is connected by a pipe 112 to a fitting 113, in the casing 98. In the chamber 100 70 the water and ozonized air first meet and are directed by the inspirating effect of the moving column of water into the mixing chamber 51, through the opening 114 and the main tube 115. The water and ozonized 105 air together pass downwardly through the tube 115, in the direction of the arrows, into the chamber 116, from which they pass through a series of smaller tubes 117 into a casing 118, and from this they pass into another series of small tubes 119, from the upper end of which they pass into the main chamber 51. After the water and ozonized 110 air are thoroughly mixed, in their passage through the various tubes described, they 115 finally pass out of the chamber 51 through the fitting 49 and the spout 48, by which the purified water is delivered.

Located at the lower end of the solenoid 89 is an air dashpot 120 containing a piston 121 connected to the solenoid core 90 by a stem 122. The piston is perforated, as at 123, and the perforation is covered by a flap valve 124, so that when the piston is moved upwardly by the stem 122, the valve is closed and the air contained within the dash pot is forced out through the pipe 125 into the annular casing 110.

When the electric solenoid is first energized, this effect, by operation of the dash-

pot, causes an impulse of air to pass through the ozone generator 100, and into the casing 70, in which the water is to be received when the valve 72 is opened, substantially at the 5 same time. After the water passes from the nozzle 75 into the opening 114 the inspirating effect of the water will have sufficient force to draw subsequent streams of air through the dashpot 120, the port 123 being 10 opened by the flap valve 124 and through the pipe 125 into the air intake of the ozone generator 100. The initial impulse of air, however, is started by the electrically energized means and subsequently maintained 15 by the inspirating effect of the flowing water.

The direction of the air through the ozone generator is shown in Fig. 10, by the arrows.

A pipe 126 passes through the water chamber 20 of the water receptacle, and the wall 41 of the chamber 44, through which wires 127, 128 may pass to the resilient, electrical conducting tongues 129, 130, respectively. These 25 tongues are supported by an insulating plate 131 which is fixed to the structure by a cleat 132. Terminals 133, 134 are secured to the plate 131 and are provided with upwardly 30 projecting contact points 135, 136, respectively. These contact points are brought into electrical connection with the relatively stationary, resilient tongues 130, 131, as clearly 35 shown in Fig. 4, when the insert supporting the operative mechanism heretofore described, is adapted to be placed in the chamber 44 and which is secured to the cover 45 of said insert.

An electric switch 140 is secured to the cover 45, consists of a plate 141 upon which is mounted a switch lever 142, pivoted, as at 40 143, and adapted to close the contacts 144, 145 when in circuit closing position. A stem 146 is supported by brackets 148, mounted upon the plate 141, and is projected through the wall 45 of the cover. On the outer end 45 is mounted a push button 149 which is held resiliently extended by a spring 150. A switch-shifting lever 151 is pivoted at 152, and is provided with a pin 153 which enters the slot 154 in the stem 146 of the switch 50 operating mechanism. The upper end of the lever 151 is enlarged, as at 156, and on the laterally extending surfaces of the enlarged head 156 are projections 157 which engage the lever 142. A spring 158, in connection 55 with the pin and slot of the stem 146, gives the switch member 142 a quick snap action when the push button 149 is pressed inwardly, as well understood by persons versed in the art, when considering devices of this 60 character. The pivoted switch member 142 will snap into connection with the contacts 144, 145, by pressure on the push button, and the spring 150 will cause it to snap out of connection when the push button 149 is released. The upper contact 144 of the switch

is connected by a wire 160 to a terminal 133 and the lower contact 145 is connected by a wire 161 with a terminal 162 and by a wire 163 to the solenoid 89 and from thence by a wire 164 with the terminal 134. This puts the 70 switch and the solenoid in series circuit with the primary circuit brought into the apparatus over the wires 127, 128. A transformer 165 is connected to the terminals 133, 134 by wires 166, 167. The secondary circuit of the 75 transformer is connected by wires 168 to one end of the ozone generator, as at 169, and the wire 170 to the terminal 171. The terminal 171 is also connected to the terminal 172 by a wire 173.

The primary circuit of the transformer is closed by the switch 140 over the circuit just described, when the push button 149 is pressed inwardly, thereby energizing the solenoid to open the water valve and energizing the ozone generator to ozonize the air drawn into and through the device by the action of the moving water.

The cover 45 containing the operative mechanism may be removed from the chamber 44 by unlocking it and by shutting off the water by closing the stop cock 54 through the opening 56 and by removing the screw 59, through the opening 63 to separate the parts 57 and 58 of the fitting 52. The latter 95 being the only part, except the electrical contact block 131, that is not removable from the chamber 44.

The faucet, or delivery spout 48, is arranged so that should a meddlesome person 100 place his finger over the delivery orifice, that water, or other liquid, would not back up into the mixing chamber and flood the ozone generator, through the pipe 112. To prevent this, I provide one or more perforations 48^a 105 in the conduit back of the delivery end of the spout, through which the liquid will flow, should the delivery end of the spout be closed.

To guard these orifices, when they are located at the end of the spout, I provide a shroud 48^b to overlie the cup-shaped terminal member 48^c. This prevents closing of the orifice 48^a by ordinary means and the orifices 110 permit the liquid to flow freely should the 115 delivery normal orifice 48^d be closed.

Besides using the apparatus for purifying water, it may be beneficially employed for many other purposes in conjunction with flowing liquids, for example, obnoxious fish 120 glue liquid may be de-odorized and made innocuous; oils may be thickened by the ozonizing process, and becoming resinous, made suitable for varnish; "aging" of certain liquids and spirits may also be accomplished 125 by the practice of my invention.

While I have herein shown a single embodiment of my invention for purposes of clear disclosure, it is manifest that changes may be made in the arrangement and con- 130

figuration of the parts within the scope of the appended claims.

Having described my invention, what I claim is:

5. 1. In a device of the character described the combination of an ozone generator to provide an ozone supply; a source of liquid supply; conduits leading from both sources of supply to a common receptacle, a casing containing said receptacle and electrical means outside of the casing to control the ozone supply and the liquid supply. 65
  2. In a device of the character described the combination of an ozone generator to provide an ozone supply; a source of liquid supply; conduits leading from both sources of supply to a common receptacle, a casing containing said receptacle and electrical means outside of the casing to simultaneously control both sources of supply. 70
  3. In a device of the character described the combination with a casing of an ozone generator to provide an ozone supply; electrical means to energize the generator; a source of liquid supply; a valve for controlling the flow of liquid from the said liquid supply; electro-responsive means for controlling said valve, all said devices within the casing and a switch outside the casing for causing said generator and said responsive means to become energized. 80
  4. In a device of the character described the combination within a casing of an ozone generator to provide an ozone supply; electrical means to energize the generator; a conduit from said generator to a mixing chamber; a source of liquid supply; a conduit from said source to said mixing chamber; a valve for controlling the flow of liquid from said supply to said chamber; an electro-responsive device for controlling said valve, all said devices within the casing and a switch outside the casing for causing said generator and said responsive device to become energized, to permit flow of said fluids. 90
  5. In a device of the character described the combination of an ozone generator to provide a supply of ozonized air; a conduit from said generator to an inspirator, through which the liquid under pressure, passes, whereby to draw air through said generator, means for controlling the flow of said liquid and means to produce a preliminary impulse of air through the ozone generator before the flow of water begins. 100
  6. In a device of the character described the combination of an ozone generator to provide a supply of ozonized air; a conduit from said generator to an inspirator to which a liquid under pressure, passes, whereby to draw air through said generator; 110
  7. In a device of the character described a closed casing; an ozone generator in said casing; a liquid conduit extending through said casing; a valve to control the flow of liquid through said conduit, within said casing, and a push button without said casing, movable to cause the valve to be opened, and to energize said generator. 115
  8. In a device of the character described, a closed casing; an ozone generator in said casing; a transformer within said casing to energize said generator; a liquid conduit extending through said casing; a valve to control the flow of liquid through said conduit, and means, without the casing, to control an electric circuit whereby to open the valve and to cause energization of said generator. 120
  9. In a device of the character described, a closed casing; an ozone generator in said casing; a transformer within said casing to energize said generator; a liquid conduit extending through said casing; an ozone and liquid mixer within said conduit; a valve within the casing to control the flow of liquid to said conduit and means without the casing to control an electric circuit whereby to open the valve and to cause energization of said generator. 125
  10. In a device of the character described, a closed casing; an ozone generator in said casing; a transformer within said casing, to energize said generator; a liquid conduit extending through said casing and terminating in a spout; an ozone and liquid mixer within said conduit; a valve, to control the flow of liquid to said conduit; an electro-responsive device in said casing to open the valve and means without the casing, to cause energization of said generator and said electro-responsive device to permit the flow of liquid and ozone through said conduit. 130
  11. In combination with a water receptacle, a casing for containing ozonizing apparatus; a shut-off stop-cock 52 within the casing communicating with said water receptacle, having a stem 54 to shut off the water accessible through an orifice in the wall of the casing and means 58, separable from said stop-cock, accessible for separation from the stop-cock through an orifice in the wall of said casing. 135
- In testimony whereof I hereunto subscribe my name.

SIEGFRIED HELD.
